COMBINED BOTTLE CAP REMOVER AND LIQUID MEASURE

Peter Mondy, Detroit, Mich., assignor to Bur-
roughs Adding Machine Company, Detroit,
Mich., a corporation of Michigan

Application July 6, 1949, Serial No. 3,725

Term of patent 14 years

(Cl. D44—29)

To all whom it may concern:

Be it known that I, Peter Mondy, a citizen of the United States, residing at Detroit, county of Wayne, State of Michigan, have invented a new, original, and ornamental Design for a Combined Bottle Cap Remover and Liquid Measure, of which the following is a specification, reference being had to the accompanying drawings, forming a part thereof.

Figure 1 is a perspective view of a combined bottle cap remover and liquid measure showing my new design;

Figs. 2 and 3 are side and rear elevations thereof; and

Fig. 4 is a top plan view thereof.

I claim:

The ornamental design for a combined bottle cap remover and liquid measure, as shown.

PETER MONDY.
